UNITED STATES PATENT OFFICE.

CLARENCE S. APPLAS, OF MOLINE, ILLINOIS.

VEHICLE-CURTAIN.

1,024,305.

Specification of Letters Patent. Patented Apr. 23, 1912

Application filed January 19, 1912. Serial No. 672,053

To all whom it may concern:

Be it known that I, CLARENCE S. APPLAS, a citizen of the United States, and a resident of Moline, in the county of Rock Island and State of Illinois, have invented an Improvement in Vehicle-Curtains, of which the following is a specification.

10 which the following is a specification.
My invention is an improvement in certain attachments for buggy, automobile, and wagon tops, which is adapted to be easily dropped and extended and to be quickly folded and slid laterally out of the way, of raised and secured at the top of the vehicle cover when not required for use.

15 The details of construction, arrangement, and operation of the attachment are as herein-after described, and illustrated in the accompanying drawing, in which—

20 Figure 1 is a vertical cross section of a portion of a vehicle top showing my curtain attachment folded, raised, and secured beneath one of the bows of the top. Fig. 2 is an enlarged cross section on the line 2—2 of Fig. 1, showing the curtain folded horizontally and secured by bands or straps. Fig. 3 is a longitudinal section of a portion of a vehicle top with my curtain attachment extended and suspended as in use. Fig. 4 is an enlarged perspective further illustrating the attachment in the same position and relation as in Fig. 3.

In the several figures, the numeral 1 indicates the curtain proper which may be constructed of leather, fabric, or any other suitable material, and having a series of glass-covered sight-holes 2 and provided with a series of vertical creases or lines of fold, as at 3. The upper edge of the curtain is doubled and provided with clips having swiveled rings 4 by which the curtain is attached slidably to a rod 5 whose attachment and adaptation for adjustment in different positions will now be described. The rod 5 is provided with an eye 6 which adapts it for pivotal and sliding attachment to a rod guide or bracket 7 that is secured to the inner side of one of the bows 8 of the vehicle top. The rod may, therefore, be swung horizontally on the bracket or slid vertically on the same as required to place it in the two positions of use and non-use, as shown in the drawing. In other words, when the curtain is required for use, the rod 5 is lowered and its free end inserted in and supported by a spring catch 9 which is attached to another bow 10 of the vehicle top, and

the curtain 1 is then drawn out or extended on the rod, as shown in Figs. 3 and 4, whereby it closes the space between the bows 8 and 10; and it is obvious that this arrangement may be employed either on the front or side of a vehicle. On the other hand, when not required for use, the curtain is folded on the lines 3 and slid along the rod 5 toward the bracket 7 into the position indicated at 11 by dotted lines in Fig. 1, the rod 5 being at the same time slid up on the bracket 7, to the position indicated in Fig. 1 and the rod supported horizontally by straps 12 that are attached to the bow 8 and their free ends provided with a spring catch 13. For holding the curtain in the position indicated by dotted lines in Fig. 1, a spring clasp 14 is employed, the same being a thin spring bar attached at one end to the rod 75 adjacent to its eye 6 and the free end of the same being bent downward and adapted to bear upon the body of the rod, which prevents the curtain rings 4 sliding accidentally along the rod and yet permits the curtain to 80 be easily drawn out by manual application of slight force. When the curtain is suspended in the position indicated at 11, it is obviously ready for instant use; but, on other occasions, as when it is apparent that 85 the curtain is not likely to be required for such use, it is folded and raised to horizontal position, as indicated at 15 in Figs. 1 and 2, the folds of the curtain thus extending parallel to, and lying close beneath, the bow 8, 90 and both the rod and curtain being supported by the straps 12, as indicated in Figs. 1 and 2.

The spring catch 9 before referred to, which serves as both support and clasp for the free end of the curtain rod 5, consists of a metal bar provided with a bent spring whose free end projects upward and is out-turned to adapt it for instant engagement of the rod therewith. 100

What I claim is:—

1. The combination with a vehicle top, of an adjustable curtain attachment comprising a curtain proper, a rod on which it is adapted to slide, and a device secured to 105 said top and serving as a pivot and slide for the rod, and means for supporting the rod in horizontal position, substantially as described.

2. The combination with a vehicle top, 110 of an adjustable curtain attachment comprising a curtain proper, a rod on which it

is adapted to slide, a bracket attached to the said top at one side and extending up along the same, an eye of the rod being adapted to swing and slide on the bracket, 5 and means for supporting the free end of the rod together with the curtain folded against it, as shown and described.

3. The combination with a vehicle top and an adjustable curtain attachment comprising a curtain proper and a rod on which the curtain is adapted to slide, means for supporting the rod horizontally, a spring clasp attached to the rod at one end and extending along the same, its free end 10 bearing on the rod and thus serving to hold the curtain in folded and vertical position, and means connected with the vehicle top for supporting the free end of the rod, substantially as described.

15

4. The combination with a vehicle top 20 having a bow extending transversely of the same and vertically on the sides, a bracket guide secured to said bow at its bend, a rod having an eye adapted to swing and slide on the bracket, a curtain provided with 25 rings adapted to slide on the rod, whereby it may be extended or folded thereon, and straps attached to the middle portion of the bow and provided at their free ends with engaging devices, whereby they are adapted to inclose the curtain and rod and support them in horizontal position contiguous to the vehicle top, as shown and described.

CLARENCE S. APPLAS.
